UNITED STATES PATENT OFFICE.

JOHN C. PARKER, OF PHILADELPHIA, PENNSYLVANIA.

SUPERHEATER-BOILER.

No. 908,882.

Specification of Letters Patent.

Patented Jan. 5, 1909.

Application filed April 8, 1905. Serial No. 254,435.

To all whom it may concern:

Be it known that I, JOHN C. PARKER, a citizen of the United States, residing at Philadelphia, in the county of Philadelphia and State of Pennsylvania, have invented 5 certain Improvements in Superheater-Boilers, of which the following is a specification.

This invention is a superheater boiler designed to generate and superheat steam so as 10 to attain the maximum efficiency. To this end it comprises a non-priming generator in combination with a superheater effecting a high rate of flow and subject to a high temperature, the rate of flow and heating maintaining a definite relation and being controlled by the distribution and regulation of the heating gases.

The presence of a very small amount of moisture in the steam delivered by the 20 generator is sufficient to destroy the efficiency of the superheater and render it a mere supplementary evaporator performing no function beyond completing the work left unfinished by the generator, and therefore 25 the design of the generator contemplates the evaporation of practically the total moisture from the steam prior to its delivery to the superheater, which conduces to uniformity and efficiency in the superheating effects.

30 A further desideratum is effected in the production of a flow through the superheater bearing a definite relation to the temperature to which the heating surface is subjected, by proportioning the sectional area of the superheater so as to secure a large difference in 35 pressure on either side thereof, preferably from three to ten pounds difference. This results in a very high rate of flow through the superheater when the generator is running 40 up to full rating, and at such times the flow of the gases on the outside of the superheating surface is correspondingly rapid in order to generate the required amount of steam. Therefore the flow of the gases and the steam 45 tend to increase or decrease together, in a more or less definite proportion to each other, and the greater the rapidity of the flow of the gas and steam at full power, the closer will the relation be maintained be- 50 tween the temperature or rate of flow of the gases and the rate of flow of the steam, for when there is a reduction in the steam con- 55 sumption the flow of the gases is reduced by partly shutting them off, which tends to maintain regularity in the temperature of the superheated steam.

The superheater is located in practically the hottest zone of the heating gases, in order that there may be obtained higher power and quicker response to varying demand for steam or the maintenance of the closest practical relation between the rates of flow of the steam and gases. The generator is especially designed for this purpose, and for practically supporting the parts of 60 the superheater, means being provided for distributing and regulating the flow of the heating gases to effect uniformity in the action of the superheater.

The nature and characteristic features of 70 the invention will more fully appear by reference to the following description and the accompanying drawings, of which:

Figure 1 represents a vertical longitudinal sectional view of a form of the apparatus; 75 Fig. 2 represents an end elevation thereof, parts being broken away for the purpose of illustration; Fig. 3 represents an end elevation of a modified construction, parts being broken away for the purpose of illustration; 80 Fig. 4 represents a transverse vertical sectional view and Fig. 5 represents a plan view of mechanism for distributing and regulating the flow of the gases in relation to the superheating tubes.

85 As shown in the drawings, the drum 1 comprises the water compartment 2 and the steam compartment 3, the compartments being connected by the ports 4 and 5 controlled by the corresponding valves 6 and 7. The water compartment communicates by the tubes 8, having the non reverse valve 9 at the outlet therefrom, with the continuous superposed feed water coils 10, extending transversely and downwardly, which discharge by way of the lower 90 coil and the uptake 11 into the steam compartment, a non return valve 12 in the steam compartment preventing flow of steam from the steam compartment through the blow off 12' when the latter is open. A pipe 100 13, connected with the upper coil beyond the non return valve 9, supplies the feed water, which is forced through the feed coils and delivered to the steam compartment 3 whence it passes into the water compartment 2. The water compartment communicates by down take tubes 14 with junction boxes 15 which discharge into the evaporating coils 16 having the non return valve 17 at the head thereof, the coils being ar- 105 ranged in four parallel sets, extending transversely and downwardly, which discharge by

way of the bottom coils of the respective sets through the uptake tubes 18 to the steam compartment. The water compartment is connected by the down-take tube or tubes 19 with a further set of continuous evaporating coils 20 having non-return valves 21 at the heads thereof, the coils extending transversely in parallel sets discharging by the respective uptake tubes 22 into the steam compartment.

The lower and upper sets of evaporating tubes are separated by a space within which is located the headers 23 and 24 and the bent superheating tubes 25 connecting them. A down take tube 26 connects the steam compartment of the drum with the header 23 which discharges by the bent tubes 25 into the header 24 discharging by the uptake tube 27 into the steam main, the caliber and number of the super-heating tubes being such that the steam is throttled in its passage therethrough with a consequent increase in velocity for the purpose specified.

The tubes 20 of the lower sets of evaporating coils support the baffle 28 having therein small holes 29 disposed to distribute the gases evolved from the fuel burning upon the grates 30. The holes 29 are arranged in pairs, each pair being controlled by a brick 31 fixed to a rod 32 for shifting it and varying the size of the holes. By means of the holes, the heating gases may be uniformly distributed, while the degree of superheat may be regulated by varying the size of the openings, thus maintaining the distribution while varying the volume of the gases impinging upon the superheating tubes. The gases passing the baffle 28 through the holes 29 and opening 29' are carried along the tubes 16 and 10 by the baffle 33 disposed between them. The grates 30, separated by the bridge wall 34, are charged from each end of the boiler through the fire doors 35.

As shown in Figs. 2 and 3, the transversely extending feed water tubes may employ various numbers of coils, being four coils high in Fig. 2 and three coils high in Fig. 3. The sets of evaporating tubes may also be varied, being five coils high in Fig. 2 and six coils high in Fig. 3. And the lower sets of evaporating tubes may also be varied, being two coils high in Fig. 2 and using a single row of tubes in Fig. 3. These variations in the arrangement of tubes will be made to suit varying conditions, it being preferable as a rule to use a single row of evaporating tubes below.

There is thus provided, as means for effecting the desired results, steam and water compartments, feed water elements connected with the steam and water compartments and placed directly beneath them in the lower temperature zones of the furnace, evaporating elements having independent connections with the steam and water com-

partments and located beneath the feed water elements in the intermediate temperature zones of the furnace, superheating elements having an independent connection with the steam compartment and located beneath the first set of evaporating elements in substantially the highest temperature zone of the furnace, and evaporating elements having independent connections with the steam and water compartments and located beneath the superheating coils, in position to support them and the means for regulating the distribution of gas in contact therewith.

By these means the feed water is heated and delivered at a uniform temperature to the water compartment, the several sets of coils for evaporating water into steam are disposed and proportioned as required for effecting the flow that has the desired relation to the temperature in the zones in which they are severally located, and the superheating surfaces are subject to a regulated distribution of approximately the highest heat of the furnace.

Having described my invention, I claim:

1. A superheater boiler comprising steam and water containing apparatus, an evaporating coil beneath said apparatus, superheating tubes beneath said evaporating coil in approximately the hottest part of the furnace, and an evaporating coil beneath said superheating tubes, said evaporating coils having independent connections with said steam and water containing apparatus.

2. A superheater boiler comprising steam and water compartments, a feed water coil beneath said compartments, an evaporating coil beneath said feed water coil, and superheating tubes beneath said evaporating coil in approximately the hottest part of the furnace, said coils and tubes having independent connections with said steam compartment.

3. A superheater boiler comprising a drum having separate steam and water compartments, continuous evaporating coils having connections with said steam and water compartments, superheating tubes beneath said evaporating coils, said superheating tubes being connected to said steam compartment, and mechanism for distributing gaseous products of combustion in relation to said superheating tubes and passing it upwardly therefrom in contact with said evaporating coils.

4. A superheater boiler comprising a drum having separate steam and water compartments, a set of evaporating coils connected with said steam and water compartments, a second set of evaporating coils beneath said first named set of evaporating coils and connected with said steam and water compartments, and a superheater having headers and tubes located between said sets of evaporat-

ing coils, said superheater being connected with said steam compartment and located in approximately the hottest part of the furnace.

5. A superheater boiler comprising steam and water compartments, a set of evaporating coils connected with said steam and water compartments, a second set of evaporating coils beneath said first named set of evapo-

10 rating coils and connected with said steam and water compartments, a superheater between said evaporating coils, and a baffle supported by said lower set of evaporating coils and having apertures therethrough for 15 distributing and directing the gaseous products of combustion in relation to said superheater.

6. A superheater boiler comprising steam and water containing apparatus, a set of 20 evaporating coils beneath and connected with said apparatus, a set of superheating tubes beneath said set of evaporating coils and connected with said apparatus, a second set of evaporating coils beneath said superheating tubes and connected with said apparatus, a perforated baffle supported by said lower set of tubes, and dampers for regulating the flow of gases through said perforations.

7. A superheater boiler comprising a fur-

nace, in combination with a plurality of sets 30 of evaporating coils, a superheater having tubes located beneath said sets of evaporating coils, an evaporating coil beneath said superheater, the upper evaporating coils occupying a lower temperature region of said 35 furnace than the lower coils and the course through each of said sets of upper coils being longer than the course through said lower coil and separate steam and water compartments with each of which the respective coils 40 are connected.

8. A superheater boiler comprising a furnace, in combination with steam and water containing apparatus, feed water coils beneath said apparatus and connected thereto, 45 a plurality of parallel sets of evaporating coils beneath said feed water coils and directly connected to said apparatus, and a superheater beneath said evaporating coils and directly connected to said apparatus. 50

In testimony whereof I have hereunto set my hand this 4th day of April, 1905, in the presence of the subscribing witnesses.

JOHN C. PARKER.
